UNITED STATES PATENT OFFICE.

DAVID S. AUSHERMAN, OF ZION CITY, ILLINOIS.

BLACKBOARD-ERASER CLEANER.

SPECIFICATION forming part of Letters Patent No. 777,582, dated December 13, 1904.

Application filed February 3, 1904. Serial No. 191,872. (No model.)

To all whom it may concern:

Be it known that I, DAVID S. AUSHERMAN, a citizen of the United States, residing at Zion City, in the county of Lake and State of Illinois, have invented a new and useful Blackboard-Eraser Cleaner, of which the following is a specification.

My invention relates to blackboard-eraser cleaners, and has for its objects to produce a comparatively simple inexpensive device of this character which will be efficient in operation and one in which the dust from the erasers will be collected during the cleaning operation.

To these ends the invention comprises the novel features of construction and combination of parts more fully hereinafter described.

In the accompanying drawings, Figure 1 is perspective view illustrating my improved device in operation. Fig. 2 is a detail longitudinal sectional elevation. Fig. 3 is a detail sectional elevation taken at right angles to Fig. 2.

Referring to the drawings, 1 designates a body or support, formed, preferably, from a single piece of board, having at one end a reduced extension or handle 2 and at its other or normally inner end a padded engaging portion 3, recessed for engagement with the ledge 4 of a blackboard, as shown in Fig. 1. The body 1 has formed therein an elongated chamber 5 of suitable dimensions, the side walls of which are composed of wire-gauze or other suitable reticulated material 6, attached to the body 1 and in turn covered by cheese-cloth or other suitable loosely-woven fabric 7, there being formed at the inner end of the body beneath the engaging portion 3 a discharge opening or passage 8, leading from the chamber 5 and normally closed by a removable plug or closure 9.

Hinged or otherwise pivoted to the reduced portion 2 and respectively on opposite sides thereof is a pair of operating members or blocks 10, carrying forwardly-extending engaging devices or guides 11, composed, preferably, of wire and each in form of an elongated U-shaped loop, presenting a pair of

spaced parallel rods 12, designed in practice to receive between them and retain the blackboard-erasers 13 and having their rear ends attached by staples or otherwise to the blocks 10.

In practice the erasers to be cleaned are inserted in the devices or guides 11, which, it is to be noted, lie parallel and in transverse alinement with the chamber 5. The engaging portion 3 is then seated upon the ledge 4, and the operator grasps the blocks 10, as indicated in Fig. 1, and manipulates them for swinging the guides 11 back and forth to beat the erasers 13 upon the reticulated sides of the chamber. During this operation the chalk-dust sifts through the said sides and settles in the chamber, where it is accumulated. After the erasers have been sufficiently cleaned they are removed from the guides, and the body has its forward end tilted downward and, if necessary, tapped upon the floor, thereby causing the accumulation of dust to settle in the opening or passage 8 for discharge by removing the closure 9.

From the foregoing it will be seen that I produce a simple efficient device for cleaning blackboard-erasers and for collecting the chalk-dust. In attaining these ends it is to be understood that I do not limit myself to the precise details herein set forth, inasmuch as minor changes may be made without departing from the spirit of the invention.

Having thus described the invention, what is claimed is—

1. In a device of the class described, the combination with a supporting member having a collecting-chamber provided with reticulated walls, of a pair of eraser-holders pivotally connected respectively with opposite sides of the support to swing toward and from the reticulated walls.

2. In a device of the class described, the combination with a supporting member having a collecting-chamber provided with reticulated walls, of a pair of operating-blocks pivotally connected respectively with opposite sides of the support, and a pair of eraser-holding guides carried respectively by the blocks

and each comprising a pair of parallel spaced members designed to receive the eraser between them.

3. In a device of the class described, the combination with a supporting member having a collecting-chamber provided with a reticulated wall, of a pervious fabric covering said wall, an eraser-holder pivotally connected with the support to swing toward and from the reticulated wall, said support having a dis-

charge - opening leading therethrough and communicating with the chamber, and a closure for said opening.

In testimony that I claim the foregoing as my own I have hereto affixed my signature in ¹⁵ the presence of two witnesses.

DAVID S. AUSHERMAN.
